[57] **ABSTRACT**

In an earth-working implement, a single ripper blade is vibrated in a horizontal direction direction normal to the of draft. of draft. The ripper blade to the mounted to the draft the blade to permit the blade to pivot about an upright itself the upright axis itself being permitted to vibrate horizontally normal to the direction of draft. Hydraulic means are provided to force the ripper blade downward.

VIBRATING RIPPER PLOW

CROSS-REFERENCE TO RELATED APPLICATIONS

This application is a continuation-in-part of my previous application filed Mar. 28, 1967, Ser. No. 626,478, now abandoned which itself was co-pending with my patent applications: Filed Apr. 2, 1965, Ser. No. 445,156, issued Pat. No. 3,396,804; Filed Sept. 29, 1966, Ser. No. 583,030, issued Pat. No. 3,448,813; Filed Jan. 24, 1967, Ser. No. 611,401, issued Pat. No. 3,508,411.

BACKGROUND OF THE INVENTION

1. Field of the Invention

This invention relates to ripper plows and more particularly to vibrating single blade rippers used for cable laying, excavating, etc.

2. Description of the Prior Art

The pulling of ripper blades which extend into the ground 2 and $\frac{1}{2}$ to 3 and $\frac{1}{2}$ feet is a difficult chore, requiring considerable power and weight upon the draft vehicle.

Vibrating rippers and vibrating single blade rippers for reducing the draft required to pull them were known to the art before this invention.

Vibrators having two shafts geared together by spur gears or chains and each shaft carrying an eccentric weight are known to the prior art. It is known to the prior art that by the timing of the gears and the placement of the weights that the resultant vibration can be made substantially unidirectional. I.e., the vibration can be made to follow a single line, e.g., a horizontal line normal to the direction of draft or a horizontal line aligned with the direction of draft or a vertical line. The vibration can be made to follow any one of these lines and have substantially no vibratory force outside of this single direction.

Considerable problems have been encountered when vibrating the ripper blade to isolate the vibrations from the draft vehicle and to force the ripper blade into the ground while still achieving the isolation. The vibrations must be isolated from the draft vehicle or the draft vehicle is severely damaged.

SUMMARY OF THE INVENTION

1. New and Different Function

I have found that if the ripper blade is vibrated about a vertical axis which is quite close to the ripper blade, substantial benefits are achieved. I achieve this particular vibration by mounting a ripper pivot having an upright axis close to the ripper itself. However, I also mount the ripper pivot itself for horizontal lateral vibration. I.e., the ripper pivot is mounted so that it bodily may move from side to side. Also, hydraulic cylinders are used to force the framework carrying the ripper pivot downward so that the ripper plow is forced into the earth.

2. Objects of the Invention

An object of this invention is to vibrate a single ripper blade for plowing deep trenches within the earth.

Other objects are to achieve the above with a device that is sturdy, compact, durable, simple, safe, efficient, versatile, and reliable, yet inexpensive and easy to manufacture, adjust, operate, and maintain.

Further objects are to achieve the above with a method that is versatile, rapid, efficient, and inexpensive and does not require skilled people to adjust, operate, and maintain.

5 The specific nature of the invention, as well as other objects, uses, and advantages thereof, will clearly appear from the following description and from the accompanying drawing, the different views of which are not necessarily to the same scale.

BRIEF DESCRIPTION OF THE DRAWING

FIG. 1 is a side elevational view of an embodiment of this invention showing a portion of the draft vehicle to which it is attached.

15 FIG. 2 is a top plan view of the embodiment of FIG. 1.

DESCRIPTION OF THE PREFERRED EMBODIMENT

20 As seen in the drawing, this earth-working implement is adapted to be attached to a draft vehicle in the form of track laying tractor 10. Frame 12 is attached to the rear of the tractor 10. The frame 12 includes plate 14 attached to the back of the tractor. It may be seen that 25 the plate is vertical and normal to the direction of draft. The direction of draft is obviously forward for the tractor. It is illustrated by Arrow A.

Two posts 16 are pivoted by pivots 18 to the plate 14. Each pivot includes ears attached to the plate 14 and tubes attached to the post with a bolt therein. The axis of the bolt and therefore the axis of the pivot is vertical or upright. Each post includes two straps 20 which are vertically oriented and spaced one from the other. Each arm 22 is pivoted by arm pivot 24 to a post 16, each pivot 24 having a horizontal axis normal to the direction of draft. The pivot 24 at the post is on the forward end of the arm 22.

30 Yoke 26 is attached by universal pivots 28 to the rear or back or after end of the arms 22. By the term "universal pivot" I mean a pivot that allows for both vertical and horizontal motion. Universal pivots may be obtained by having two pivots, one with a vertical axis and one with a horizontal axis or by having a ball socket joint. I prefer to use a ball socket type universal pivot at the rear of each of the arms 22 to attach to the yoke 26.

35 Ripper pivot 30 at the middle of the yoke 26 attaches ripper holder 32 to the yoke 26. The ripper pivot 30 is a particularly heavy duty pivot which is capable of transmitting the entire draft of the tractor 10 to ripper blade 34. It may be seen that the blade 34 has a length which is vertical and a width which extends in the direction of draft and it will be moved through the earth in a direction of the forward edge of the ripper blade. In addition, the ripper pivot 30 is capable of transmitting downward thrust to the ripper blade 34 or, also, upward thrust to the ripper blade 34. In addition to these criteria, the ripper pivot 30 is capable of withstanding the vibratory forces and motion which will be imposed upon it.

40 The ripper pivot 30 has a vertical or upright axis in normal operation. It is described as an upright axis, however, it will be understood by those skilled in the art that when the ripper blade 34 is raised, the pivot axis at that time will be angled and perhaps more horizontal than vertical. However, in operation, it is definitely upright and it is illustrated as being vertical. The

ripper blade 34 is securely attached to the ripper holder 32. Vibrator 36 is attached to the ripper holder 32, and, therefore, is attached or connected to the ripper blade 34. The vibrator has two rotating shafts, each with eccentric weights thereon so it is a means for vibrating the blade 34 with an alternating force, the force being horizontal and normal to the direction of draft. The shafts are rotated at a speed of between 300 and 500 rpm so that the vibration frequency is between 300 and 500 cycles per minute. The direction of the vibration is shown by double headed Arrow V.

The vibrator may be driven from any of several sources. I prefer to use hydraulic vibrator motor 38, which is conveniently attached to the vibrator housing itself. The hydraulic hoses supplying hydraulic fluid under pressure to the motor 38 have not been shown for clarity.

The arms 22 may be raised and lowered about the arm pivots 24 by lifting hydraulic cylinders 40. One of the hydraulic cylinders 40 on each side extends from an upper attachment at or near the top of the post 16 to an attachment on the arms 22 at about mid-point of the arms. It will be understood that the hydraulic cylinders 40 are connected by hydraulic lines to a source of hydraulic fluid under pressure. However, for clarity of the drawings, the hydraulic lines have not been shown inasmuch as they are so standard upon mechanical equipment of this nature. It will be understood that the lifting hydraulic cylinders 40 are double acting cylinders so they can force the ripper blade 34 into the earth as well as lift it for transportation.

Erecting hydraulic cylinder 42 extends from the upper central area of the plate 14 to upper knee 44 on the top of the ripper holder 32. Since the knee 44 is attached to the holder, it is also attached to the ripper blade 34 and, therefore, may be thought of as a portion thereof. It will be understood that without a stiff or compression member extending to the ripper holder 32 above the universal pivots 28, the ripper blade 34 would not remain erect or in proper plowing position in the ground. Also, the digging angle of the blade may be adjusted by adjusting the length of the hydraulic cylinder 42. The erecting cylinder 42 is connected to the top of the knee 44 by universal pivot 50. In this case, the pivot is in the form of two single pivots, one with a vertical axis and the other with a horizontal axis. Likewise, the erecting hydraulic cylinder 42 is connected to the plate 14 by universal pivot 52. Also, the hydraulic lines for the erecting hydraulic cylinder have not been shown for clarity.

Furthermore, when the blade 34 is removed from the ground, if the erecting cylinder 42 is fully contracted, this tilts up the blade 34 so that it tends to be raised higher from the ground.

The ripper holder 32 also has pneumatic tires 46 mounted thereon.

Since one of the principal uses of rippers of this sort is to lay cables, chute 48 for the purpose of laying cable has been illustrated in FIG. 1.

Therefore, it may be seen in operation when the vibrator 36 causes a horizontal vibration normal to the direction of draft upon the blade 34, this causes the blade to at least have some vibratory motions about the ripper pivot 30. However, it will also be understood that the vibration of the blade will not be limited to this and, furthermore, the ripper pivot 30 itself will have translational vibratory motion in a horizontal direction

normal to the direction of draft. This is because posts 16 are pivoted to the plate 14 by the pivots 18 with an upright axis, therefore, the entire yoke 26 can move from side to side as seen by double headed Arrow Y. The pivots 28 are universal and, therefore, will permit limited side to side movement at the connection between the arms 22 and the yoke 26. By describing the particular principal vibrations, I do not intend to say there are not other vibrations.

The embodiment shown and described above is only exemplary. I do not claim to have invented all the parts, elements or steps described. Various modifications can be made in the construction, material, arrangement, and operation, and still be within the scope of my invention. The limits of the invention and the bounds of the patent protection are measured by and defined in the following claims. The restrictive description and drawing of the specific example above do not point out what an infringement of this patent would be, but are to enable the reader to make and use the invention.

I claim as my invention:

1. In an earth-working implement having
  - a. a single ripper blade having length and width
  - b. extending with its length upright into the earth,
  - c. a frame to which the ripper blade is attached, and
  - d. draft means connected to the frame for moving the ripper blade through the earth in a direction of draft which is the direction of one edge of the ripper blade;
  - e. The improvement comprising:
    - f. a ripper pivot having an upright axis interconnecting the blade and frame,
    - g. vibration means attached to the ripper blade for vibrating the blade with an alternating force in a horizontal direction normal to the direction of draft,
    - h. said frame forming a means
      - i. for permitting vibratory horizontal movement of the ripper pivot normal to the direction of draft, and
      - ii. for applying downward pressure to the ripper blade through the ripper pivot,
    - j. said frame includes:
      - i. an upright plate normal to the direction of draft attached to the draft means,
      - ii. a pair of parallel posts,
      - iii. each post pivoted to the plate by pivots with upright axes;
      - iv. an arm pivoted at its forward end to each post,
      - v. each arm pivoted to the post by a pivot with horizontal axis normal to the direction of draft,
      - vi. a lifting hydraulic cylinder extending from each post to said arm connected thereto to raise and lower the arms,
      - vii. a yoke connecting the after ends of the arms,
      - viii. universal pivots connecting each arm to the yoke,
      - ix. said ripper pivot on said yoke, and
      - x. an erecting hydraulic cylinder extending from the plate to structure attached to the ripper blade.

2. The invention as defined in claim 1 with an additional limitation of
the erecting cylinder

- i. attached to plate by a universal pivot and
- ii. attached to the upper part of the ripper blade structure by a universal pivot.

3. The invention as defined in claim 2 with an additional limitation of
pneumatic tires attached to the ripper blade.
